CLAIM

The ornamental design of a material feed finger, as shown and described.

DESCRIPTION

FIG. 1 is a perspective view of a material feed finger of our new design;

FIG. 2 is a top plan view thereof, the bottom plan view being a mirror image thereof;

FIG. 3 is a front elevational view thereof, the rear elevational view being a mirror image thereof;

FIG. 4 is an end elevational view of the left end thereof;

FIG. 5 is an end elevational view of the right end thereof;

FIG. 6 is a perspective view of a first modification of the material feed finger of FIG. 1;

FIG. 7 is a top plan view of FIG. 6, the bottom plan view being a mirror image thereof;

FIG. 8 is a front elevational view of FIG. 7, the rear elevational view being a mirror image thereof;

FIG. 9 is an end elevational view of the left end of FIG. 6; and,

FIG. 10 is an end elevational view of the right end of FIG. 6.
